ARCH SUPPORTER

Joseph Ruig Rigandi, Staten Island, N. Y.

Application May 25, 1935, Serial No. 23,363

2 Claims. (Cl. 36—71)

This invention relates to improvements in the art of shoes and more particularly it pertains to arch supporters for shoes.

It is the primary object of the present invention to provide a new and novel construction of arch supporter for shoes which may be incorporated directly in a shoe at the time of building, or which may be equally adapted to a device separate and apart from the shoe but adapted to be employed therein.

A further object of the invention is to provide a device of the afore-mentioned character which is especially adapted to embodiment in ladies' shoes particularly where the shank or arch portion is, due to the extreme height of the heel, extraordinarily high.

Other objects will become apparent as the nature of the invention is better understood and reference will, therefore, be had to the accompanying drawing wherein;

20 Figure 1 is a longitudinal sectional view of a lady's shoe of the high heel type showing an arch supporter constructed in accordance with one form of the present invention embodied therein,

25 Figure 2 is a top plan view of the insole of the shoe shown in Figure 1,

Figure 3 is a bottom plan view of said insole,

Figure 4 is a fragmentary top perspective view 30 thereof,

Figure 5 is a detail perspective view of an arch supporting pad,

Figure 6 is a transverse sectional view taken substantially on the line 6—6 of Figure 3,

35 Figure 7 is a similar view with the arch supporting pad in place, and;

Figure 8 is a similar view illustrating the arch supporting pad securing means in place.

In that form of the invention illustrated in 40 Figures 1 to 8, inclusive, in which the invention is illustrated as embodied in a lady's shoe of the high arch and high heel type, the insole is designated 20. This insole may be formed from any suitable insole material cut to the proper shape to fit the style or type of shoe in which it is to be employed.

A member 21 of relatively thin leather or other suitable material which is shaped substantially as illustrated, is secured to the under or inner face of the insole 20, in any desired manner, but preferably by the stitching 23. This member 21 projects slightly beyond one edge of the insole as illustrated at 24, and as best illustrated in Figures 3, 7 and 8, this portion 24 55 is curved upwardly so that it will conform gen-

erally to the contour of the inner longitudinal arch of a human foot and this shaping may be accomplished in any desired manner. However, I prefer to shape the member 21, in this type of device, by circumflexing it into the desired shape before it is attached to the insole, and so attaching it to the insole, that it will maintain its circumflexed form after it is secured thereto. Suitable perforations 25 are preferably formed in the insole 20 and the member 21, and other perforations 26 may be formed in the member 21. These perforations are not, however, essential to the invention.

The reference character 27 designates an arch supporting pad formed from any suitable soft compressible material, of which sponge rubber is one very good example. This arch supporting pad is shaped in the desired manner to provide a relatively thick outer portion and a relatively thinner inner portion 29, and when in position 20 in the shoe, the relatively thicker outer portion is adapted to underlie the projecting portion 24 of the member 21, as best illustrated in Figures 7 and 8. The arch supporting pad 27 may be secured in place by securing it in any desired manner preferably by cementing it to a member 30 formed from relatively thin leather or other suitable material, which in turn may be cemented or otherwise fastened to the insole 20.

Thus it will be apparent that when the insole 30 is in position within a shoe, the arch supporting pad will be properly positioned to provide the correct support for the inner longitudinal arch of the foot to which the shoe may be applied.

It is to be understood that the insole 20 may 35 be either the type which is removable with respect to the shoe, or permanently built therein and furthermore, in lieu of a full insole, a relatively short insole may be employed.

From the foregoing it is apparent that the 40 present invention provides a new and improved arch supporter which may be built either permanently in a shoe or, if desired, may as heretofore described be constructed in the form of a detachable member adapted for use in a shoe 45 and be removably associated therewith.

While the invention has been disclosed in its preferred form it is to be understood that it is not to be limited to the specific construction illustrated and that it may be practiced in other 50 forms within the scope of the appended claims without departing from the spirit thereof.

Having thus described the invention, what is claimed as new, is;

1. An arch support for shoes comprising an 55

- insole member adapted to be positioned in a shoe, said insole member being shaped to conform to the shank portion of the shoe, an arched member secured to the under face of said insole
8 member and conforming in shape to the inner longitudinal arch of a human foot, said arched member having one of its side edges extended beyond the adjacent side edge of the insole member, an arch supporting pad cemented to the
10 under face of said arched member, the outer edge of said arch supporting pad extending beyond the adjacent edge of the insole and terminating short of the outer edge of the arched member, and a relatively thin flexible member
15 cemented to the arch supporting pad and to the arched member.

2. An arch support for shoes comprising an insole member adapted to be positioned in a shoe,

said insole member being shaped to conform to the shank portion of the shoe, an arched member secured to the under face of the insole member and extending throughout the width thereof, said arched member conforming in shape to 5 the inner longitudinal arch of a human foot and having one of its side edges extended beyond the adjacent side edge of the insole member, an arch supporting pad having a thick portion and a thin portion, and means for securing said 10 arch supporting pad to the under face of the arched member with its thick portion positioned beneath the outer edge portion of the arched member, said securing means comprising a relatively thin flexible member cemented to the arch 15 supporting pad and to the arched member.

JOSEPH RUIG RIGANDI.
